VACUUM PRODUCING MEANS FOR FUEL
DEVICESWilliam A. Edwards, Chicago, and Charles S.
Burton, Oak Park, Ill.

Application August 25, 1930. Serial No. 477,548

6 Claims. (Cl. 123—139)

The purpose of this invention is to provide a means for producing vacuum in a vacuum-operated device auxiliary or appurtenant to a motor vehicle having an internal combustion engine 5 motor, and particularly for operating a vacuum fuel feeding device or vacuum-operated windshield wiper, or other appurtenant or auxiliary devices and apparatus which have customarily hitherto been arranged to derive suction for producing vacuum from the intake manifold of the engine.

The invention consists in the elements and features of construction shown and described as indicated in the claims.

15 In the drawing:

Figure 1 is a diagrammatic view showing a motor vehicle having a vacuum tank for supplying fuel to the engine connected for operation in accordance with this invention.

20 Figure 2 is a detail section at the line, 2—2, on Figure 1 on an enlarged scale.

Figure 3 is a section axial with respect to the exhaust pipe showing the connection for deriving suction from the exhaust flow in accordance 25 with this invention.

Figure 4 is a section axial with respect to the suction ducts and check valves therein seen in Figure 1.

30 Figure 5 is an interior view of a valve construction which may be substituted for the check valves seen in Figure 4 and located at the junction of the two suction ducts seen in that figure.

Figure 6 is a view similar to Figure 3 showing 35 a preferred form of suction duct connection with the exhaust conduit.

Figure 7 is a sectional view of the suction connection with the intake manifold showing the expedient illustrated in Figure 6 applied for enhancing the suction derived from the intake manifold.

Figure 8 is a section at the line 8—8 on Figures 6 and 7.

45 It is well known that a defect constituting at times an objection to all familiar types of vacuum tanks designed to be employed for supplying fuel to internal combustion engines, arises from the circumstance that when the engine is running at high speed with wide open throttle, as when the vehicle is climbing a steep hill, with the engine running "in low", the degree of vacuum in the intake manifold is low and liable to be insufficient for lifting the fuel from the main tank, 50 which under such circumstances being at the

rear of the vehicle, is depressed relatively to the vacuum tank and carburetor.

The present invention obviates this deficiency of the vacuum tank by affording means for producing a vacuum in the vacuum tank which is 60 not wholly dependent upon the degree of vacuum in the intake manifold.

This means consists in utilizing in addition to or in alternation with the suction derivable from the intake manifold of the engine, the engine 65 exhaust pressure preferably derived from a selected cylinder of a multiple cylinder engine, and the velocity of the exhaust gas stream for producing suction through a duct leading from the vacuum chamber of a vacuum tank and 70 discharging in the exhaust passage, preferably at a flow accelerated constriction of said passage.

Referring to the drawing,—Figures 1, 2 and 3:

The vacuum tank, A, has its vacuum chamber, 20, connected by a suction pipe, 21, to an engine 75 exhaust pipe, 30, said exhaust pipe being furnished with a Venturi constriction, 32, and the suction pipe, 21, being connected to the exhaust pipe proximate to the Venturi constriction, as seen at 33.

A pipe, 41, connected at 42 with a suction pipe, 21, leads thence to a connection with the manifold intake engine indicated at 40. Upon considering this construction, it will be understood 85 that at all times when the engine is in operation producing a discharge of the exhaust gases, the high pressure of the exhaust causing rapid flow of the gases through the exhaust pipe, 30, will operate for lowered pressure at the apex of the Venturi constriction, tending to cause inflow 90 through the suction pipe, 21, and producing vacuum in the vacuum chamber of the vacuum tank. It will be recognized that upon starting the engine by a starter the exhaust pressure will be negligible, and that consequently if the vacuum tank is empty at starting the operation of the engine by the starter will not produce the suction necessary for filling it and supplying the engine

with fuel to cause it to operate normally in response to the action of the starter. And it will also be recognized that under some running conditions the exhaust pressure may be insufficient to produce effective suction for lifting the fuel to the vacuum tank. This deficiency of the method consisting in utilizing exhaust pressure for producing suction is obviated by connecting to the suction pipe, 21, a pipe, 41, shown thus connected at 42, said pipe leading for connection to the intake manifold as indicated at 40. 100 Upon considering this construction it will be 105

110

recognized that the suction derivable from the intake manifold of the engine when the engine is being operated by the starter, being positively produced by the intake stroke of the engine 5 tons, will operate for filling the vacuum tank, so that there will be fuel to supply the engine and cause it to respond by normal operation to the action of the starter; and it will also be recognized that the running conditions under which 10 the exhaust pressure is lowest, and liable to be deficient for the purpose of producing the desired suction, are those under which the intake manifold vacuum is greatest, so that the deficiency of the suction derivable from the exhaust pressure 15 is obviated by the suction derived from the intake manifold at such stages in the operation of the engine.

It may be expected that under circumstances rendering the exhaust pressure very low while 20 the intake manifold vacuum is high, the suction of the latter might tend to draw gases from the exhaust pipe into the intake manifold; and on the other hand, it may be expected that under circumstances rendering the exhaust pressure very 25 high, as when the engine is running at high speed with wide open throttle, the suction developed in the suction pipe, 21, might so far exceed the suction produced in the pipe, 41, by the intake manifold vacuum that the intake manifold might 30 get exhaust gases through the pipe, 31. These undesirable possibilities are avoided and their happening is prevented by providing in the pipe connections antecedent to the junction, 42, check valves opening for flow by suction only away 35 from that junction, and seating against reverse flow. Thus the valve, 50, in the pipe, 31, between the connection of that pipe with the exhaust pipe branch and the junction, 42, with the intake manifold pipe connection, will be seated if at 40 any time the suction from the intake manifold shall be greater than the suction through the pipe, 21, due to the exhaust velocity; and the valve, 60, provided between the intake manifold and the junction, 42, will be seated if at any 45 time suction due to the exhaust pressure and velocity of exhaust flow should be greater than that derived from the intake manifold.

It will be obvious that a single double-acting 50 valve device located at the junction, 42, can be arranged to act with the same effect as the two 55 separate valves above described in the positions shown. Such a single valve arrangement is illustrated in Figure 5, the operation of which will be understood from the drawing, the pipes 21^x, 31^x, and 41^x, corresponding to the pipes, 21, 31 and 41, respectively of Figure 4, and the single valve, 50^x, performing the function of the two valves, 50 and 60, of Figure 4.

It has been found most convenient and most 60 effective for the purposes of this invention to utilize the exhaust from an individual cylinder or one or more individual cylinders of the engine rather than the exhaust from the exhaust manifold. By making connection with an individual 65 cylinder at a point in the length of the cylinder which will be passed by the piston in about the first quarter of its exhaust stroke, the maximum exhaust pressure is utilized without the point of 70 connection being uncovered for an objectionable portion of the compression stroke (during which if said port were uncovered combustible gas mixture would be discharged), and at the same time and by the same expedient consisting in selecting 75 the location of the port, the pressure due to the explosion in the ignition phase of the engine cycle

is operative during the one-fourth of the piston stroke which occurs after it passes the port in the power stroke of the piston.

Upon considering this construction, it will be recognized that after the exhaust stroke in which the exhaust pressure operates as described, the intake stroke will operate for intake or suction and not for discharge and pressure. It being found that a very small aperture serves for communicating very adequate pressure for the purpose of the invention by reason of the very high pressure that is operative in the exhaust stroke and in the power stroke, as above mentioned, it results that with this very small aperture the suction developed in the intake stroke is relatively negligible, as might be expected in view of the fact that only the pressure of one atmosphere, fifteen pounds, operates for intake, whereas the pressure in the power stroke and even the exhaust pressure at its maximum, each amount to many atmospheres.

The suction derived in the manner illustrated in Figure 3 is in part caused by the lowering of pressure in the Venturi constriction of the exhaust passage which is due to the velocity of the exhaust current past the orifice which constitutes the suction duct inlet, and in part caused by the frictional entrainment by the exhaust gas current of the air exposed at the end of the suction duct constituting said port. The element of suction due to entrainment may be materially increased by any construction which increases the area of the air exposed to the frictional action of the exhaust gas current; and the form shown in Figure 6 accordingly yields a higher degree of suction than the form shown in Figure 3, since in the form shown in Figure 6 the suction duct terminal is a somewhat extended nozzle, 34, positioned axially with respect to the exhaust passage and the Venturi element thereof, and longitudinally slotted, as indicated at 35, 35, 35, 35, for exposing the air within the nozzle throughout the entire area of the slots at the outer surface of the nozzle to the friction of the exhaust gas current.

A similar expedient may be employed for increasing the suction derived from the intake manifold, as illustrated in Figure 7, which shows the exhaust duct, 44, formed with a Venturi section, 45, in which there is positioned a nozzle, 46, which constitutes the terminal of the duct, 41^a, which leads from the check valve, 60, for discharge in the intake manifold.

It will be recognized that the construction shown at this point is what is commonly called a vacuum booster; but the boosting or increase of degree of vacuum which it yields is very greatly enhanced by the provision of the slotted nozzle shown.

We claim:

1. In combination with an apparatus having a chamber in which a vacuous condition is to be produced and an internal combustion engine with which said apparatus is associated, means for producing the vacuous condition consisting of an engine exhaust pipe and a suction pipe leading from said chamber and connected for discharge in said exhaust pipe with relation to the flow passage of said exhaust pipe suitable for inducing suction through said suction pipe, the exhaust pipe being connected for exhaust pressure with a single selected cylinder of the engine.

2. In combination with an apparatus having a chamber in which a vacuous condition is to be produced and an internal combustion engine with which said apparatus is associated, means for producing the vacuous condition consisting of

- an engine exhaust pipe and a suction pipe leading from said chamber and connected for discharge in said exhaust pipe with relation to the flow passage of said exhaust pipe suitable for inducing suction through said suction pipe, the exhaust pipe being connected for deriving exhaust pressure with a single selected cylinder of the engine at a point in the length of the cylinder which will be passed and the port covered by the piston in the early part of the exhaust stroke. 5
3. In combination with an apparatus having a chamber in which a vacuous condition is to be produced and an internal combustion engine with which said apparatus is associated, means for producing the vacuous condition consisting of an engine exhaust pipe and a suction pipe leading from said chamber and connected for discharge in said exhaust pipe with relation to the flow passage of said exhaust pipe suitable for inducing suction through said suction pipe, and a second suction pipe communicating with the intake manifold of the engine and connected with the first mentioned suction pipe, the exhaust pipe being connected for deriving exhaust pressure with a single selected cylinder of the engine at a point in the length of the cylinder which will be passed and the port covered by the piston in the early part of the exhaust stroke. 10
- 15 5. In combination with an apparatus having a chamber in which a vacuous condition is to be produced and an internal combustion engine with which said apparatus is associated, means for producing the vacuous condition consisting of an engine exhaust pipe and a suction pipe leading from said chamber and connected for discharge in said exhaust pipe with relation to the flow passage of said exhaust pipe suitable for inducing suction through said suction pipe, and a second suction pipe communicating with the intake manifold of the engine and connected with the first mentioned suction pipe, the exhaust pipe being connected for deriving exhaust pressure with a single selected cylinder of the engine at a point in the length of the cylinder which will be passed and the port covered by the piston in the early part of the exhaust stroke. 15
- 20 6. In combination with an apparatus having a chamber in which a vacuous condition is to be produced and an internal combustion engine with which said apparatus is associated, means for producing the vacuous condition consisting of an engine exhaust pipe and suction pipe leading from said chamber and connected for discharge in said exhaust pipe with relation to the flow passage of said exhaust pipe suitable for inducing suction through said suction pipe, and a second suction pipe communicating with the intake manifold of the engine and connected with the first mentioned suction pipe, the exhaust pipe being connected for deriving exhaust pressure from a single selected cylinder of the engine and the port of communication of the cylinder with said pipe being restricted relatively to the size of the pipe, whereby intake from and suction resulting in said connected pipe in the intake stroke of the piston is rendered negligible in comparison with the normal pressures which result in the power and discharge strokes of the piston. 25 100
- 30 7. In combination with an apparatus having a chamber in which a vacuous condition is to be produced and an internal combustion engine with which said apparatus is associated, means for producing the vacuous condition consisting of an engine exhaust pipe and suction pipe leading from said chamber and connected for discharge in said exhaust pipe with relation to the flow passage of said exhaust pipe suitable for inducing suction through said suction pipe, and a second suction pipe communicating with the intake manifold of the engine and connected with the first mentioned suction pipe, the exhaust pipe being connected for deriving exhaust pressure from a single selected cylinder of the engine, and the port of communication of the cylinder with said pipe being restricted relatively to the size of the pipe, whereby intake from and suction resulting in said connected pipe in the intake stroke of the piston is rendered negligible in comparison with the normal pressures which result in the power and discharge strokes of the piston. 35 110
- 40 8. In combination with an apparatus having a chamber in which a vacuous condition is to be produced and an internal combustion engine with which said apparatus is associated, means for producing the vacuous condition consisting of an engine exhaust pipe and suction pipe leading from said chamber and connected for discharge in said exhaust pipe with relation to the flow passage of said exhaust pipe suitable for inducing suction through said suction pipe, and a second suction pipe communicating with the intake manifold of the engine and connected with the first mentioned suction pipe, the exhaust pipe being connected for exhaust pressure with a single selected cylinder of the engine. 45 115
